UNITED STATES PATENT OFFICE.

ANNA J. SCHLUNKE, OF FARGO, NORTH DAKOTA.

GRAVITY GRAIN-SEPARATOR.

1,353,856.

Specification of Letters Patent. Patented Sept. 28, 1920.

Application filed August 2, 1919. Serial No. 314,994.

To all whom it may concern:

Be it known that I, ANNA J. SCHLUNKE, a citizen of the United States, residing at Fargo, in the county of Cass and State of North Dakota, have invented new and useful Improvements in Gravity Grain-Separators, of which the following is a specification.

The object of my present invention is the provision of a grain separator in which the 10 operation is effected entirely by gravity, and which is therefore extremely simple and inexpensive in construction as well as durable, the latter being largely due to the fact that it is unnecessary to incorporate movable 15 parts in the separator.

To the attainment of the foregoing, the invention consists in the peculiar and advantageous gravity grain separator herein-after described and definitely claimed.

20 In the drawings, accompanying and forming part of this specification:

Figure 1 is a longitudinal, vertical section of the separator constituting the best practical embodiment of my invention that I 25 have as yet devised.

Fig. 2 is a transverse section taken in the plane indicated by the line 2—2 of Fig. 1, looking toward the left.

Similar numerals of reference designate 30 corresponding parts in both views of the drawings.

Among other elements my novel separator comprises spaced and inclined side frames 1. These side frames 1, together 35 with a hopper 2 that is arranged to discharge in the space between the upper ends of the side frames, are supported by a framework 3.

In furtherance of my invention I arrange 40 in inclined position between the side frames 1, two chutes 4 and 5, the contiguous ends of which are spaced apart, as indicated by 6. Also in furtherance of my invention I provide the chute 4 at its lower end with a 45 lip 7, while at the upper end of the chute 5 I provide a flange 8, the latter being of greater depth than the lip 7 in about the proportion illustrated. It will also be observed that the contiguous ends of the straight portions 50 of the chutes 4 and 5 are arranged in substantially the same inclined plane.

By virtue of the described relative arrangement of the chutes 4 and 5, it will be observed that when grain is fed into the 55 hopper 2, the same will gravitate down the chute 4. The wheat units being smoother

and heavier than the wild oat and "King-head" units, will be caused by the lip 7 to bound or jump over the flange or blade 8, while the comparatively heavy and rough 60 wild oat and "Kinghead" units will drop through the space 6.

From the lower end of the chute 5 the wheat units are discharged to a supplemental lower chute 5^a, carried between the frame sides 1 and having a flange or blade 8^a at its upper end. I prefer to employ in combination with the chutes hereinbefore described a supplemental chute 4^a which is arranged with its upper portion opposite 70 the space 6, and is provided at its lower end with an upturned lip 7^a. The scheme of my invention as elaborated is adapted to meet the condition that some of the wheat units will fail to jump across the space 6 and will 75 fall with the oat units and the "King-head" units through the said space 6. Therefore I provide the supplemental chute 4^a. The wheat units together with the oat and "Kinghead" units will pass down the 80 said chute 4^a, and then the operation before described will be repeated—i. e., the wheat units will jump across to the chute 5^a, while the oat and "Kinghead" units will drop 85 through the space between the lip 7^a and the flange 8^a, and will be discharged from the separator on the chute 9^a.

I would also have it understood that my separator may be used to advantage in the separation of mustard seed from flax, and 90 water grass and other weed seeds from hay seeds.

It will be apparent from the foregoing that notwithstanding its simplicity and durability, my novel separator is expeditious and thorough in operation.

Having described my invention, what I claim and desire to secure by Letters-Patent, is:

A grain separator comprising spaced 100 frame sides, a hopper arranged to discharge grain between the upper portions of said frame sides, means supporting the frame sides and the hopper, an upper inclined chute arranged to receive grain from the 105 hopper and extending in inclined position downwardly between the frame sides and having an upwardly directed lip at its lower end, a lower chute arranged in inclined position between the frame sides and with its 110 upper end below and spaced from the lip at the lower end of the upper chute, a flange

reaching upwardly from the upper end of the lower chute, said flange being of greater depth than the lip of the upper chute, a chute arranged between the frame sides in position to receive grain from the lower of said chutes, a chute arranged between the frame sides in position to receive grain from the space between the first-named chute and second-named chute and having a lip at its

lower end, a reversely-inclined chute in communication with the space between the lip of the fourth-named chute and the third-named chute, and an upstanding flange arranged between and common to the third-named chute and the fifth-named chute. 10 15

In testimony whereof I affix my signature.

ANNA J. SCHLUNKE.
